UNITED STATES PATENT OFFICE.

EUGENE T. SPECHT, OF CHICAGO, ILLINOIS, ASSIGNOR OF ONE-HALF TO
ERNEST A. EASTMAN, OF CHICAGO, ILLINOIS.

CAST-OFF.

SPECIFICATION forming part of Letters Patent No. 705,622, dated July 29, 1902.

Application filed January 2, 1902. Serial No. 88,100. (No model.)

To all whom it may concern:

Be it known that I, EUGENE T. SPECHT, a citizen of the United States, residing at Chicago, in the county of Cook and State of Illinois, have invented certain new and useful Improvements in Cast-Offs, of which the following is a specification.

My invention relates to a new and improved clip designed, primarily, to be used as a cast-off or connection between the main strap and tabs of suspenders or similar articles, and is designed to produce a device of the class described that shall be extremely simple in its construction and which instead of yielding 15 under any stress that normally tends to open the connection shall be made tighter thereby.

Referring to the accompanying sheets of drawings, in which the same reference characters are used to designate identical parts in 20 all the figures, Figure 1 is a front elevation of a suspender-end, showing my improvement as applied between the tab and the main strap of a suspender. Fig. 2 is an enlarged elevation of the clip in connection with the 25 main-strap and tab connections. Fig. 3 is a central section on the line A A of Fig. 2. Fig. 4 is a similar view showing a slightly-modified construction. Fig. 5 is an elevation of the main-strap connection as modified for 30 use with the modified form of clip shown in Fig. 4. Fig. 6 is a view similar to Fig. 1, but showing another form of a clip made of spring-wire instead of a spring-plate. Fig. 7 is a perspective view of the modified form of 35 clip. Fig. 8 is an elevation of this form of clip as applied to the main-strap and tab connections, and Fig. 9 is a central section on the line B B of Fig. 8.

a is the main strap or webbing, which is 40 provided with the buckle b, through which the main strap passes and to which its end is secured to form a loop by which the main-strap connection c is supported.

d is the tab, which may be of any desired 45 construction and has the tab connection e at the top thereof.

The cast-off clip f, which is the vital feature of my invention, is made of some resili- 50 ent substance, such as spring sheet metal, which is worked into the form shown and which consists of the plate-like front portion g and the somewhat-similar rear portion h,

which are connected by the loop or angle j, which is so shaped as to prevent the upper cross-piece of the tab connection e from rising 55 therein and which also has the angle forming the lower portion thereof sufficiently acute so that if the tab connection be pulled down, while the clip is held up the upper cross-bar of the tab connection will tend to 60 separate the two portions g and h. The front portion g has formed at its upper ends the hooks or jaws k, which are separated by the recess l, through which an oppositely-facing hook or jaw m on the rear portion 65 passes, the relation of these jaws being such that when the front and rear portions are separated, as by the previously-explained action of the tab connection resulting from a downward pull, the jaws will be brought more 70 firmly together, thus preventing the lower portion of the main-strap connection, which they embrace, from being freed therefrom. By the construction shown and described it 75 will be apparent that the greater the longitudinal strain between the strap and the tab the tighter the cast-off clip will hold the two connections. At the same time when it is desired to use the clip as a cast-off all that is necessary is to press the front and rear portions thereof together until they assume the 80 position indicated in dotted lines in Figs. 3 and 4, in which the main-strap connection can be readily detached.

In Figs. 4 and 5 I have shown a slightly-modified form of construction in which the jaw m' on the rear portion has its end turned 85 rearwardly and horizontally instead of extending substantially vertically upward, so that it is adapted to pass into a slot c', formed 90 in the lower part of the main-strap connection in position to coöperate therewith. It will be apparent that this modification, so far as the increasing of the clamping effect under a pull is concerned, will operate in the same 95 manner as the form first described and can also be used in the same manner as a cast-off. It will also be perceived that this form has the additional advantage of holding the main-strap connection somewhat more securely 100 than does the first-described form.

In Figs. 6 and 9 I have illustrated another form of my invention, in which the clip is made of spring-wire. As before, a is the

main strap, *b* is the buckle, *c* is the main-strap connection, and *d* the tab, having the tab connection *e* at the top thereof.

The clip *f'*, as shown best in the perspective view of Fig. 7, will be seen to correspond closely to the outlines of the other form of clip and to be constructed of a single piece of wire, which is bent to form the front portion *g'*, the rear portion *h'*, and the loops *j'*, which 10 coöperate with the upper portion of the tab connection in exactly the same manner as in the form previously described. The hooks or jaws *k'* are separated by a loop *l'*, and I conveniently terminate the ends of the wire 15 in the horizontal portion of this loop, where they are held together by a small cylindrical tube *l'*. The jaw *m'* on the rear portion passes through the loop *l'*, and the two jaws thus formed coöperate with the lower portion 20 of the main-strap connection in the manner previously described.

It will be apparent that these cast-off clips can be used either side up—that is, with the jaws coöoperating with the main strap connection, as shown in Figs. 1 to 7, or with the tab connection, as shown in Figs. 8 and 9—the principle and method of operation remaining the same in both positions in which the cast-off clip may be placed.

30 It will be apparent that the cast-off clip herein described may be constructed of any material having the necessary resiliency and strength and that it may be covered with leather, celluloid, or any other material that 35 may be desired to give it smoothness or finish. It is a single integral piece, as distinguished from one where two or more parts are employed and jointed together to have the necessary relative movement.

40 While I have shown my invention as embodied in the form which I at present consider best adapted to carry out its purpose, it will be understood that it is capable of modifications and that I do not desire to be 45 limited in the interpretation of the following claims except as may be necessitated by the state of the prior art.

What I claim as new, and desire to secure by Letters Patent of the United States, is—

1. In a device of the class described, the combination with the main-strap connection and the tab connection, of a resilient integral cast-off clip between them having a loop embracing one connection and a pair of jaws the other, said connections and cast-off being so shaped that any pull on the connections tends to cause the jaws to hold the connection which they embrace more firmly. 50

2. In a device of the class described, the combination with the main-strap connection 60 and the tab connection, of a resilient integral cast-off clip between them having an angular loop embracing one connection and a pair of crossed jaws embracing the other connection, the operation of a pull between the connections being to cause the connection in the loop to expand the clip to bring the jaws more firmly together upon the other connection. 65

3. In a device of the class described, the combination with the main-strap connection 70 and the tab connection, of a resilient integral cast-off clip between them having the loop *j* embracing the upper cross-piece of the tab connection and having the jaws *k* separated by the recess *l* through which the jaw *m* passes, 75 the said jaws embracing the lower cross-piece of the main-strap connection; substantially as described.

4. In a device of the class described, the combination with the main-strap connection 80 and the tab connection, of a resilient integral cast-off clip between them having a loop embracing one connection and a pair of crossed jaws the other connection, one of said connections being provided with the slot *c'* into 85 which the end of the jaw *m'* is adapted to pass; substantially as and for the purpose described.

In testimony whereof I affix my signature in presence of two witnesses.

EUGENE T. SPECHT.
